UNITED STATES PATENT OFFICE

FRANKLIN W. KOHLER, OF CHICAGO, ILLINOIS

CHAIR CONSTRUCTION

Application filed July 28, 1927. Serial No. 209,053.

This invention relates to improvements in chair constructions, and has for its object to provide a new and improved device of this description. The invention has a further object to provide a chair construction which can be adjusted to change its width. The invention has a further object to provide a chair construction whereby two chairs can be made up into a bed or berth. The invention has further objects which are more particularly pointed out in the accompanying description.

In the drawings I have illustrated one form of my invention.

Figure 1 is a plan view showing two chairs embodying the invention adjusted to form a berth or bed;

Fig. 2 is a side elevation of the construction illustrated in Fig. 1;

Fig. 3 is a sectional view taken on the line 3—3 of Fig. 4;

Fig. 4 is a front elevation of one of the chairs shown in Fig. 1 with the back cushion removed and the chair adjusted to widen it;

Fig. 5 is a view similar to Fig. 4 with the chair in its normal unadjusted position;

Fig. 6 is an enlarged sectional view taken on the line 6—6 of Fig. 5;

Fig. 7 is a bottom view of the seat cushion;

Fig. 8 is a plan view of the chair in its unadjusted position with the cushions partly broken away;

Fig. 9 is a bottom view of the chair removed from its pedestal;

Fig. 10 is an enlarged view of the control handle for the locking pin;

Fig. 11 is an enlarged sectional view taken on the line 11—11 of Fig. 8;

Fig. 12 is an enlarged sectional view taken on the line 12—12 of Fig. 4;

Fig. 13 is an enlarged sectional view taken on the line 13—13 of Fig. 8;

Fig. 14 is a back view of the chair in its adjusted position with parts broken away;

Fig. 15 is a sectional view taken on the line 15—15 of Fig. 5;

Fig. 16 is a view of the rear face of the back cushion;

Fig. 17 is a sectional view taken on the

line 17—17 of Fig. 2 when the chair is in its unadjusted position;

Fig. 18 is an enlarged sectional view taken on the line 18—18 of Fig. 5.

Like numerals refer to like parts throughout the several figures. The present chair is of the general type illustrated in my co-pending application number 209,052 filed of even date herewith.

In the particular construction illustrated herein the chair is rotatably mounted upon a pedestal 1 by means of a base 2, the base and pedestal being rotatably connected together by means of the shaft 3 which extends into both of them (see Fig. 6) so as to form a strong, durable rotatable connection. The pedestal 1 is provided with a series of openings 4. The base 2 has connected therewith a pin 5 which has one end adapted to project into one of said holes to lock the base and pedestal together. The pin is provided with a shoulder 6 which limits its downward movement and is pressed downwardly by the spring 7 contained in the housing 8. The pin 5 is provided with the engaging part 9 by means of which it is lifted through the agency of the inclined lifting face 10 connected with the rod 11 which is mounted in the bracket 12 and which has a handle 13. The bracket 12 is connected with the base 80 plate 14. When the rod 11 is moved inwardly the pin 5 is lifted to remove it from the opening 4 and the chair may then be rotated with relation to the pedestal to any desired position. Upon releasing the rod 11 the 85 spring 7 moves the end of the pin 5 into one of the openings 4 to lock the base and pedestal together.

The chair is provided with a bottom 15 and a sliding bottom plate 16. The chair is 90 provided at one side with an arm consisting of the member 17 connected with the sliding bottom plate 16 and the cushion 18. At the other side is an arm consisting of the member 19 connected with the bottom 15 and 95 the cushion 20. The back of the chair consists of three sections relatively slideable, namely the back sections 21, 22, and 23. The back section 21 is connected with the bottom 15 and with the arm member 19. The back 100

section 22 is connected with the sliding bottom plate 16 and the arm member 17. The back section 23 is slidably mounted between the other two back sections. As herein shown, the back section 23 is slidably mounted on a guide 24 carried by the section 22 and is provided with a pin 25 which extends through a slot 26a in the section 22. A lever 26 is pivotally mounted upon the pivot 27 and is provided with a pin 28 which works in a slot 29 in the back section 23. Associated with the lever on the other side of the pivot is a projection 30 which, when the bottom and the sliding bottom plate are moved, causes the lever to move the section 23 outwardly to its exposed position as shown in Fig. 4. The bottom 15 and sliding bottom plate 16, when the chair is in its unadjusted position, are locked together by the locking pin 31 (see Fig. 6). This locking pin also locks the parts when they are in their adjusted position. Some means is provided for moving this pin to its unlocking position.

As before stated, the bottom and sliding bottom plate may be slid relatively to widen the chair. Both the bottom and the sliding bottom plate may be slid rearwardly so that the base plate 14 will project to act as a rest for the backs of the chair when a bed or berth is formed as shown in Fig. 1. If it is desired to simply widen the chair, the locking pin 31 is moved so as to be moved out of the hole 32 in the sliding bottom plate but to remain in the hole in the bottom 15. This permits the sliding bottom plate and bottom to be moved relatively to widen the chair but prevents the bottom and the sliding bottom plate from being moved rearwardly. When it is desired to move the bottom and the sliding bottom plate rearwardly, the pin 31 must be given a great movement so as to remove it not only from the opening in the sliding bottom plate, but from the opening in the bottom 15 so as to release the bottom 15 from the base plate 14. I have shown a single mechanism for giving this pin these two movements.

The locking pin 31 is normally forced to its locking position by the spring 33 in the housing 34 and is provided with a stop 35 which limits its movement. This locking pin is provided with engaging part 36 adapted to be engaged by an arm 37 connected with the rock shaft 38 (see Figs. 6, 9, and 10). The shaft 38 is mounted in suitable bearings on the base and is connected by an arm 39 with a controlling rod 40. This rod is slidably and rotatably mounted in suitable bearings and is provided with the controlling handle 41 by means of which it is rocked. The rod 40 is provided with a projection 42 which engages a cam 43 having two cam faces, a short cam face 44 and a longer cam face 45. When the controlling rod 40 is rocked so as to move the projection 42 along the short

cam face 44 the rod is moved longitudinally so as to rock the shaft 38 and move the arm 37 to move the pin 31 so as to remove it from the opening 32 in the sliding bottom plate 16 but still maintain it in the opening in the bottom 15. The sliding bottom plate 16 and the back sections 22 and 23 may then be slid so as to widen the chair as shown in Fig. 14. This movement is stopped by stop 16b on plate 16 engaging shoulder 16c on member 16d attached to bottom 15, Fig. 1.

After the chair has been widened, the handle is released and the spring 33 moves the locking pin 31 into the opening 46 (see Fig. 8) in the sliding bottom plate 16 so as to lock the parts together. If now it is desired to move the bottom and sliding bottom plate rearwardly on the base plate 14 or if, when the chair is in its unadjusted position, it is desired to move the sliding bottom plate laterally and the bottom and the sliding bottom plate rearwardly, the handle 41 on the rod 40 is moved in the opposite direction. This moves the projection 42 along the longer cam face 45 which moves the rod a greater distance longitudinally thus moving the arm 37 a greater distance and a distance sufficient to remove the locking pin 31 from the bottom 15. The sliding bottom plate may now be moved to one side and both the bottom and the sliding bottom plate moved rearwardly, the parts taking the position shown in Figs. 1, 2, and 4.

When the handle is released the spring then moves the locking pin into the opening 47 in the bottom 15 (see Fig. 6) and into the opening 48 (see Fig. 8) in the sliding bottom plate 16. The parts are then locked in their adjusted position. The several parts are moved with relation to each other by grasping the upper parts of the chair as, for example, the arms and separating the arms and moving them rearward.

Each chair is provided with a bottom cushion 48 which has at its rear bottom edge the projecting plate 49 which extends under the back cushion support 50 (see Figs. 6 and 7). This bottom cushion is also provided with a projection 51 (see Fig. 7) which is connected to a bar 52. This projection, when the chair is widened, is engaged by the engaging part 53 (see Fig. 1) on the sliding bottom plate so as to move the bottom cushion out from under the arm cushion 20 as shown in Fig. 4 the movement being stopped by 51 engaging shoulder 51a, (Fig. 1). When the sliding bottom plate is slid in the other direction to close up the chair an engaging part 54 engages the projection 51 and moves the bottom cushion back under the arm 20 as shown in Fig. 5.

The chair is provided with a back cushion 55 which has at its lower edge a grooved holding piece 56, into the groove of which is received the support 50 (see Fig. 6). A guiding

device 57 is also provided which guides the back cushion into position. The back cushion is provided at the top with a slot 58 which has the enlarged portion 59. The back section 21 is provided with a looped part 60 having attached thereto a pin 61 provided with a head 62. This head is inserted in the enlarged portion 59 of the slot 58 and the cushion is then moved until the pin 61 enters the smaller portion of the slot. This holds the top of the back cushion in place. The back section 23 is provided at the top with a guide 63 and at the bottom 64, the two guides being connected with the back section 22. The loop 60 attached to the back section 21 acts as a top guide for the back section 22. The lower end of this back section works on a guide 65 connected with the back section 21. The back cushion 55 is also provided with a series 20 of openings 66 (see Fig. 16).

The base plate 14 of each chair is provided with the projections 67 (see Figs. 1 and 2). When the chairs are in their adjusted position to form a berth the backs are placed 25 between them and rest on the projecting edges of the base plates and the projections 67 enter the opening 66 so as to prevent accidental movement of the back cushions. When the sliding bottom plate 16 is moved outwardly 30 to widen the chair to form a bed or berth it is supported upon the support 68 attached to the wall 69 of the car or other device in connection with which the chairs are used (see Fig. 4). The arm cushion 18 is removable 35 from the arm member 17 and is placed in between the bottom cushion 48 and the arm member 17 as shown in Fig. 4. The arm cushion 18 is removably connected with the arm member 17 by means of a pin 70 (see Fig. 11) 40 which enters a slot 71 in the arm member 17 and which is provided with a large end 72 which prevents lateral movement of the arm cushion. The cushion is removed from the arm section 17 by lifting the cushion so as 45 to remove the pin from the slot.

When the chairs are to be used as ordinary chairs they are in their unadjusted position as shown in Fig. 5. When it is desired simply to widen the chairs the handle 41 is moved 50 to move the projection 42 along the short cam face 44. This moves the pin 31 from the hole in the sliding bottom plate 16 and permits said plate and the back sections to be slid so as to widen the chair as shown in Fig. 55 14. The bottom cushion 48 is moved out from under the arm cushion 20 as shown in Fig. 4 and the arm cushion 18 may then be placed 60 between its end and the arm member 17 as shown in Fig. 4 thus providing a double seat, 65 that is, a chair in which two people may sit. When it is desired to form a bed or berth the handle 4 is moved in the opposite direction to move the projection 42 along the long cam face 45. This removes the locking pin 31 70 from the holes in the sliding bottom plate 16

and the back sections may then be moved to widen the chair and they may also be moved rearwardly so as to cause the base plate 14 of each chair to project outwardly. The two chairs when in this projected position are facing each other with the bottom cushion 48 and the arm cushions 18 in the position shown in Fig. 4. The back cushions are then removed and placed between the chairs, resting on the projecting ends of the base plate 14 as shown in Figs. 1 and 2. The device is then ready to receive the ordinary bed clothing so that it may be used as a bed or berth. When used as berths in cars, the ordinary partitions 73 are placed between the berths above the backs of the chair as shown in Figs. 2 and 4.

It will be seen that by the means of this construction the chairs may be used as single chairs and they may be adjusted so as to form double chairs, that is, so as to seat two people in each chair and they may be arranged so as to form a bed or berth. When these chairs are used in sleeping cars, the cars may be used as chair cars in the daytime and sleeping cars at night, thereby reducing the number of cars necessary on any given line. This for example, permits a car that required a day to run say between stations, to be run in the daytime between these stations as a chair car and to be run back at night between them as a sleeping car, thus permitting each car to be run continuously and making one car do the work of two cars, namely a chair car and a sleeping car. The base plate 14 is provided with guides 14a which fit between the bottom 15 and the angle pieces 15a. The bottom 15 and associated parts slide back and forth on these guides 14a as the chair is changed from a chair to a bed and from a bed to a chair. The sliding movement is limited by the stops 15b on the angle pieces 15a and the stops 14b on the base plate 14. The back section 21 is provided with a projection 21a which engages the arm member 17 as shown in Fig. 15 when the parts are in their closed or chair position. The support 68 attached to the wall of the car is provided with projections 68a which fit into recesses in the chair arm so as to hold the arm cushion in the proper position. The movable plate 23, (see Fig. 6) is so mounted in guides 63 and 24 as to afford the greatest freedom of lateral movement and to also hold it away from back plates 21 and 22 so as to prevent scratching of the finish.

I claim:

1. A chair construction comprising a base, a bottom, a sliding bottom plate slidably connected with said bottom, said bottom and sliding bottom plate movably mounted on said base so that they may be moved with relation thereto, a single locking device adapted to lock the bottom and the bottom sliding plate together and to lock said bottom and

bottom sliding plate to said base, a handle for controlling said locking device, said handle when moved in one direction adapted to disconnect the sliding bottom plate from the bottom so that it may be moved out to widen the chair and when moved in another direction adapted to disconnect the sliding bottom plate and the bottom from said base so that they may be moved with relation to the base.

10. 2. A chair construction comprising a base, a bottom, a sliding bottom plate, a locking pin connected with said base and projecting through said bottom and said sliding bottom plate, a handle and means controlled by the same handle for moving said locking pin to release the sliding bottom section and for giving it a further movement to release the sliding bottom section and bottom from the base so that they may be moved with relation to the bottom.

15. 3. A chair construction comprising a base, a bottom, a sliding bottom plate, a locking pin connected with said base and projecting through said bottom and said sliding bottom plate, a handle and means controlled by the same handle for moving said locking pin to release the sliding bottom section and for giving it a further movement to release the sliding bottom section and bottom from the base so that they may be moved with relation to the bottom, to an adjusted position, said sliding bottom section and bottom being provided with means which, in their adjusted position, permit said pin to engage and hold them in such adjusted position.

20. 4. A chair construction comprising a base, a bottom, a sliding bottom plate connected with said bottom, an arm connected with said bottom and provided with a cushion, a cushion on said bottom plate, said cushion being provided with a projection on its lower face, two separated engaging parts on said sliding bottom plate, one adapted to engage said projection to move the end of the bottom cushion out from under the arm cushion when the plate is moved outwardly, the other adapted to engage said projection to move the end of said bottom cushion under said arm cushion when said plate is moved back to its initial position.

25. 5. A chair construction comprising a base, a bottom slidably connected with said base and formed of two sections slidably connected together, a single pin movably connected with said base, the two sections of the bottom having registering openings into which the pin is adapted to be received, means for moving said pin to disconnect the two sections of the bottom from each other but maintain the connection between one section of the bottom and said base, and means for further moving said pin so as to release both sections of the bottom from said base.

30. 6. A chair construction comprising a base, a bottom slidably connected with said base

and formed of two sections slidably connected together, a single pin movably connected with said base, the two sections of the bottom having registering openings into which the pin is adapted to be received, a rod having an operative connection with said pin and adapted when moved longitudinally, to move said pin, a handle connected with said rod, means for moving said rod longitudinally a predetermined distance when the handle is moved in one direction, and means for moving said rod longitudinally a greater distance when the handle is moved in the other direction.

7. A chair construction comprising a base, a bottom slidably connected with said base and formed of two sections slidably connected together, a single pin movably connected with said base, the two sections of the bottom having registering openings into which the pin is adapted to be received, a rod operatively connected with said pin adapted to move said pin when the rod is moved longitudinally, an engaging part on said rod, a cam having two cam faces, one of greater length than the other, the engaging part being located between said cam faces, the cam faces adapted to move the rod longitudinally when the shaft is rocked in either direction, one of the cam faces causing the rod to move a greater distance longitudinally than the other cam face.

8. A chair construction comprising a base, a bottom slidably connected with said base and formed of two sections slidably connected together, a single pin movably connected with said base, the two sections of the bottom having registering openings into which the pin is adapted to be received, an arm connected with said pin, a rock shaft with which said arm is connected, a rod adapted, when moved longitudinally, to rock said rock shaft, an engaging part on said rod, a cam having two faces of different lengths, one of said cam faces adapted to be engaged by said engaging part when the rod is rocked in one direction, the other cam face adapted to be engaged by said engaging part when the shaft is rocked in the other direction.

9. A chair construction comprising a base, a bottom, a sliding bottom plate adapted to be slid laterally to widen the chair, a bottom cushion, means connected with said bottom plate for moving the cushion when the sliding bottom plate is moved in either direction, and stops for limiting the movement of said sliding bottom plate and cushion.

10. A chair construction comprising a base, a base plate fixed thereto, a bottom formed of sections slidably connected together, one of said sections adapted to be moved toward and away from the front of the device, a back formed of sections overlapping from front to rear and slidably connected together.

11. A chair construction comprising a base, a bottom, a sliding bottom plate slidably connected with said bottom, and movable with relation thereto independent of said base, the bottom and sliding bottom plate being movably mounted on said base so that they may be moved with relation thereto, and a single locking device for locking the bottom and sliding bottom plate in their initial and in their moved positions and means at a distance from said locking device for controlling its position.

Signed at Chicago, county of Cook and State of Illinois, this 8th day of July 1927.

15 FRANKLIN W. KOHLER.
